James Patterson, of Elizabeth, N. J.
assignor to

Deborah, Albert and Nathaniel Powers of Newburgh, N. Y.

Letters Patent No. 514 - Dated Oct. 31-1865.

Design for a Floor Oil Cloth Pattern.

The schedule referred to in these letters Patent and making part of the same.

To all whom it may concern:

Be it known that I, James Patterson, of the City of Elizabeth, County of Union and State of New Jersey, have invented or produced a new and original design for Floor Oil Cloths or other fabrics, and I do declare that the following is a full and exact description of the same, viz: The outline of the pattern is made by narrow white bands so disposed as to form the pattern into squares with flattened hexagons interposed between them. The squares are of lighter colored ground than the hexagons and are ornamented with thirty figures; the hexagons with arabesque figures.

And what is claimed as my invention and desired to be secured by letters Patent is The design for Floor Oil Cloths or other fabrics as shown upon the accompanying drawings which are hereby declared to be a part of the foregoing specification.
